WILLIAM C. CARTER, OF ST. LOUIS, MISSOURI, ASSIGNOR TO CARTER CARBURETOR COMPANY, OF ST. LOUIS, MISSOURI, A CORPORATION OF MISSOURI.

CARBURETER.

1,222,848.

Specification of Letters Patent. Patented Apr. 17, 1917.

Application filed September 8, 1913. Serial No. 788,632.

To all whom it may concern:

Be it known that I, WILLIAM C. CARTER, a citizen of the United States, residing at St. Louis, Missouri, have invented a certain new and useful Improvement in Carbureters, of which the following is a full, clear, and exact description, such as will enable others skilled in the art to which it appertains to make and use the same.

10 This invention relates to carbureters, and has for its main object to provide an inexpensive carbureter of simple construction that is economical in the consumption of fuel and which will produce a uniform mixture at all speeds of the motor.

Another object is to provide an efficient carbureter which is not equipped with an air valve or other moving parts that are apt to get out of adjustment or which can be 20 adjusted improperly by an unskilled user.

Another object is to provide a carbureter in which the fuel-supplying device is of sufficient capacity or size to supply a relatively great quantity of fuel at slow engine speeds, and means is provided for diminishing the suction on said fuel-supplying device progressively as the speed of the motor builds up or increases so that said device will not supply proportionately the same 25 quantity of liquid fuel at high speeds that it does at slow speeds of the motor.

And still another object is to provide a carbureter in which the liquid fuel-supplying device and the means for diminishing the suction on said device progressively as the speed of the motor increases, are arranged below the level of the fuel in the float chamber of the carbureter and are so designed that the weight or pressure of the 35 liquid fuel, or, in other words, the tendency of the fuel to seek its level, causes the suction on the fuel-supplying device to increase progressively as the speed of the motor decreases. Other objects and desirable features of my invention will be hereinafter 40 pointed out.

Briefly described, my improved carbureter consists of a fuel-supplying device of sufficient capacity or size to supply a relatively 50 great quantity of liquid fuel at slow engine speeds, an accelerating reservoir into which the liquid fuel is fed from said device, preferably by means of gravity, and means whereby variations in the level of the liquid fuel in said accelerating reservoir diminishes

or increases the suction on said fuel-supplying device, thereby preventing the relatively great quantity of liquid fuel that is supplied at slow speeds from increasing proportionately with the speed of the motor. The carbureter is also preferably provided with a starting reservoir for holding a sufficient quantity of liquid fuel to cause the motor to start easily.

Figure 1 of the drawings is a vertical sectional view of a carbureter constructed in accordance with my invention;

Fig. 2 is a horizontal sectional view taken on the line 2—2 of Fig. 1;

Fig. 3 is a horizontal sectional view taken on the line 3—3 of Fig. 1;

Fig. 4 is a horizontal sectional view taken on the line 4—4 of Fig. 1; and

Figs. 5 and 6 are detail vertical sectional views illustrating a short nozzle and a long 75 nozzle, respectively.

Referring to the drawings which illustrate the preferred form of my invention, A designates a casting that is provided with a vertically disposed tubular-shaped portion 80 1 whose upper end flares outwardly and merges into an annular portion or ring 2 on the under side of a horizontally disposed plate portion 3 that is adapted to be attached to the intake pipe of the motor on 85 which the carbureter is used. The throttle valve 4 is oscillatingly mounted inside of an open-ended sleeve 5 that is arranged vertically in the plate portion 3 concentric with the annular-shaped portion 2, said sleeve 90 being spaced away from the inner surface of the annular portion 2 and the lower end of said sleeve terminating above the flared upper end of the tubular-shaped portion 1 of the carbureter. Air-openings 6 are 95 formed in the annular-shaped portion 2 and in the flared part of the tubular-shaped portion 1, as shown in Figs. 1 and 3, so as to permit air to enter the lower end of the sleeve 5 and become mixed with the rich 100 charge of combustible gas that flows upwardly through said sleeve when the throttle valve is open.

The casting A is arranged at one side of the float tank 7 of the carbureter and the bottom 8 of said float tank is formed by a casting which is provided at one side with a laterally projecting portion 8^a through which the lower end of the tubular-shaped portion 1 of the casting A passes, said parts 110

being secured together in any suitable manner. The means herein shown for connecting said parts together consists of a nut 9 threaded into the lower end of said tubular-shaped part 1 and provided with a head 9^a that bears against the under side of the part 8^a of the casting 8 and thus clamps a flange 10 on said tubular-shaped part 1 tightly against the upper side of the part 8^a. The 10 needle-valve 8^b and the mechanism that is used for governing said valve may be of any preferred type or design, the mechanism herein shown being like that illustrated and described in my prior Patent No. 1,019,948, 15 dated March 12, 1912.

A fuel-supplying device which consists of a nozzle 11 is screwed into the upper end of the nut 9, said device being preferably provided with a single supply port or jet 11^a of sufficient size to supply a relatively great quantity of liquid fuel at slow engine speeds. The liquid fuel flows from the float tank into an annular duct 12 in the part 8 and thence through ports 13 and 14 in the tubular-shaped part 1 and in the nut 9, respectively, up through the fuel opening in the nozzle 11 that leads to the jet 11^a, said member 1 and nut 9 being preferably provided with a plurality of ports 13 and 14, as shown in 25 Fig. 1, so as to cause the fuel to flow freely into the nozzle. The nut 9 forms a closure for the lower end of the tubular-shaped part 1 of the carburetor, and a partition 15 is arranged in said tubular-shaped part 1 at a 30 point above the upper end of the nut 9 so as to form an accelerating reservoir or chamber α . A hollow member 16, which I will term a mixing nozzle, is arranged inside of the accelerating chamber α concentric with 35 the nozzle 11 and extends from the bottom to the top of said chamber, said member 16 being substantially tubular-shaped and provided with a dome-shaped upper end in which a discharge port or jet 17 is formed. The 40 dome-shaped upper end of the mixing nozzle 16 projects upwardly through an opening in the partition 15, and a plurality of ports 18 are formed in the side of said mixing nozzle 16 at different levels for a purpose 45 hereinafter described. The main nozzle or fuel-supplying device 11 and also the mixing nozzle 16 are both located below the level of the fuel in the float tank so that the tendency of the fuel to seek its level will 50 cause said nozzles to be completely submerged in liquid fuel when the motor stops and when it is running idle, the fuel escaping from the nozzle 11 into the mixing nozzle 16 and thence through the side ports 55 18 in the mixing nozzle into the accelerating reservoir. The fuel also escapes through the discharge port 17 in the mixing nozzle into a starting reservoir γ which is located above the partition 15, as shown in Fig. 1. The 60 partition 15 may be retained in position in

various ways but I prefer to form an annular flange 19 on the inner side of the tubular-shaped member 1 so as to form a stop against which the partition 15 is clamped by means of the mixing nozzle 16, the lower end of said mixing nozzle being seated in an annular groove formed in the nozzle 11, which, as previously stated, is screwed into the nut 9.

A liquid fuel duct 20 leads upwardly 75 from the starting reservoir γ , preferably from the bottom of said starting reservoir, to an annular mixing chamber 21 that surrounds the open-ended sleeve 5 in which the throttle valve is located. Air is admitted 80 to the mixing chamber 21 by means of a pipe 22 that leads into said chamber, as shown in Fig. 2, so as to form a combustible mixture for starting the motor, the air-pipe 22 being preferably arranged adjacent 85 to or in contact with the exhaust pipe or some other heated part of the motor so as to supply heated air to the mixing chamber 21. The combustible mixture from the mixing chamber 21 is preferably introduced 90 into the intake pipe of the motor in such a manner that the fuel and air constituting said mixture will become thoroughly mixed before entering the cylinders of the motor and thus insure charges of equal richness 95 to all of the cylinders of the motor, and in the embodiment of my invention herein shown, this is effected by means of one or more tangentially disposed ports 21^a formed in the upper end portion of the sleeve 5 preferably at a point above the throttle valve, said tangentially disposed ports causing the mixture to escape from the mixing chamber 21 and travel upwardly through the intake pipe of the motor with a circular or whirling 100 action. While I have herein shown the fuel supply ports 21^a located above the throttle valve, it is not essential to the successful operation of my carburetor that said ports should be located in the exact position 105 shown, so long as they are arranged in such a manner that a comparatively strong suction will be exerted on the fuel duct 20 when the motor is throttled down.

In order to prevent the relatively great 115 quantity of liquid fuel that is supplied at slow engine speeds from increasing proportionately with the speed of the motor I have provided means for admitting air to the accelerating reservoir α so as to diminish the 120 suction on the fuel supply port 11^a of the nozzle 11 progressively as the speed of the motor increases. In the carburetor herein shown air is admitted to the accelerating reservoir α by means of a pipe 23 which may be 125 arranged inside of the tubular-shaped part 1 of the carburetor, with its upper end communicating with the atmosphere and its lower end communicating with alining holes formed in the flange 19 and in the partition 130

15 which bears against said flange, as shown clearly in Fig. 1. The liquid fuel duct or bypass 20 is also preferably formed by a small pipe, and both of the pipes 20 and 23 5 are arranged in hollow ribs 24 formed on the tubular-shaped portion 1 of the casting A, as shown in Figs. 1 and 4, the lower end of the fuel-pipe 20 communicating with a horizontally-disposed hole in the flange 19 10 whose outer end terminates at the inside edge of said flange, as shown in Fig. 1, so that the liquid fuel in the starting reservoir y will be drawn upwardly through the bypass 20 when a suction is created in the 15 mixing chamber 21. The carbureter is provided with the usual drain-cock 25 which is preferably screwed into the lower end of the nut 9 that forms a closure for the lower end of the tubular-shaped part 1 of the carbureter.

As soon as the motor stops the liquid fuel escapes from the supply port 11^a of the nozzle 11 into the mixing nozzle 16 and thence from the nozzle 16 into the accelerating reservoir x and into the starting reservoir y, 25 as shown in Fig. 1, this, of course, being due to the fact that said nozzles and reservoirs are located below the level of the fuel in the float tank. When the motor is cranked 30 the liquid fuel in the starting reservoir y is sucked up through the duct 20 into the mixing chamber 21 where it combines with the air admitted to said mixing chamber through the pipe 22 so as to form a starting charge 35 that is injected tangentially into the intake pipe of the motor through the port or ports 21^a that are located above the throttle valve. At idle speeds of the motor; or, in other words, when the motor is running with a 40 closed throttle and no load, the bypass or duct 20 also serves to supply the fuel to the motor. At slow engine speeds sufficient suction is created to exhaust the charge of fuel in the starting reservoir and cause fuel to 45 be drawn from the accelerating reservoir x through the discharge port 17 of the mixing nozzle 16 upwardly through the tubular-shaped portion 1 of the carbureter, said fuel mingling with the air that is drawn into the 50 open-ended sleeve 5 through the air-openings 6 and thus forming a combustible gas of the proper richness to run the motor. The particles of fuel which are too heavy to 55 be drawn upwardly through the tubular-shaped portion 1 by a slight suction drop to the bottom of the starting reservoir y and are sucked upwardly into the mixing chamber 21 by the intense suction in the bypass 20. Consequently, there is no liability of 60 the heavy particles of fuel collecting on the walls of the main suction passageway 1 of the carbureter and thus choking the motor when the throttle valve is opened quickly, owing to the fact that the bypass 20 leads 65 from a point above the throttle valve to a

point in the main suction passageway at which the heavy particles of fuel tend to collect when the motor is throttled down. When the suction increases sufficiently to lower the level of the liquid fuel in the accelerating reservoir x, air starts to flow into said reservoir through the pipe 23 and thus diminishes the suction on the nozzle 11. In other words, when the suction in the main suction passageway 1 is sufficient to suck the liquid fuel out of the mixing nozzle 16, the level of the fuel in the reservoir x drops as the suction increases and air rushes into said reservoir and thence into the mixing nozzle through the side ports 18 in said nozzle, 70 thereby diminishing the suction on the main fuel nozzle 11 progressively as the speed of the motor increases. By providing the mixing nozzle 16 with a plurality of side ports 18 arranged at different levels, the quantity 75 of air that enters said nozzle will increase progressively as the level of the fuel in the reservoir x drops or as the suction in the tubular-shaped portion 1 of the carbureter increases so that by the time the motor is 80 running fast enough to suck the fuel directly out of the nozzle 11, air will be rushing into the mixing nozzle through all of the side ports 18 in same and consequently will prevent an excessive flow of fuel from the 85 nozzle 11. The air that is admitted to the accelerating reservoir x through the air-pipe 23 not only diminishes the suction on the nozzle 11 progressively as the speed of the motor builds up or increases, but it also 90 mingles with the fuel that escapes from the nozzle 11, the result being a partial mixing of the air and fuel before the fuel emerges from the top port 17 in the mixing nozzle and comes in contact with the air that is 95 sucked in through the air openings 6 in the annular-shaped portion 2 of the carbureter that surrounds the open-ended sleeve in which the throttle valve is arranged. When 100 the speed of the motor diminishes, the fuel 105 starts to flow into the accelerating reservoir x and rise in same progressively as the speed of the motor decreases. By the time the engine is traveling at slow speed the fuel will 110 completely fill the accelerating reservoir and 115 as no air will be entering said reservoir the suction in the carbureter will be sufficient to insure a relatively great supply of liquid fuel. It will thus be seen that the advantage derived from arranging the nozzles 11 120 and 16 and the reservoirs x and y below the level of the fuel in the float chamber is that gravity is utilized to force the fuel into said reservoir so as to progressively cut down the admission of air to the accelerating reservoir as the speed of the motor diminishes. If the motor on which the carbureter is to be used, produces a slight suction, the carbureter will be provided with a short nozzle 11, as shown in Fig. 5, or, in other words, 130

a nozzle whose jet 11^a is located far enough below the level of the fuel in the float chamber to increase the pressure of the fuel at the jet 11^a sufficiently to compensate for the slight suction of the motor. If the motor produces a strong suction, the carbureter will be equipped with a long nozzle, as shown in Fig. 6, so as to reduce the pressure of the fuel at the jet 11^a. The cross sectional area of the accelerating reservoir α may be varied or changed so as to increase or decrease the quantity of fuel contained in said reservoir and thus adapt the carbureter to any particular motor. In other words, if the motor on which the carbureter is to be used requires a great deal of fuel to accelerate, the accelerating chamber α will have to be made larger in cross sectional area than that of a carbureter which is adapted for a motor that accelerates on a small quantity of fuel.

A carbureter of the construction above-described is economical in the consumption of fuel, it insures a mixture of the proper richness at all speeds of the motor, it produces a starting charge of the proper richness that whirls upwardly through the intake pipe of the motor in a circular path, it insures a sufficient supply of liquid fuel to start the motor easily and run the motor at slow speeds without liability of supplying an excessive quantity of liquid fuel when the motor is running at high speed. The carbureter is of simple construction and comprises so few parts that it can be manufactured at a very low cost, and it is not provided with an air valve or other adjustable or moving parts that are apt to get out of adjustment or which can be adjusted improperly by an unskilled user.

Having thus described my invention, what I claim as new and desire to secure by Letters Patent is:

1. A carbureter provided with an accelerating reservoir that holds the fuel which is supplied to the motor until comparatively high speed is attained, a vertically-disposed nozzle arranged inside of said reservoir and provided at its upper end with a discharge opening through which fuel is discharged into the air passageway of the carbureter, said nozzle having a plurality of ports located at different levels, a port for supplying liquid fuel to said nozzle, and an air supply duct having its upper end terminating in the air passageway of the carbureter and its lower end communicating with said accelerating reservoir above the level of the fuel therein so as to cause the suction on said supply port to vary as the level of the fuel in said accelerating reservoir varies.

2. A carbureter provided with an accelerating reservoir from which the supply of fuel is drawn until comparatively high

speed is attained, a vertically-disposed nozzle arranged inside of said reservoir and provided at its upper end with a discharge opening and at its side with a plurality of ports located at different levels, a port for supplying liquid fuel to said nozzle, means for supplying air to said accelerating reservoir above the level of the fuel therein so as to cause the suction on said supply port to vary as the level of the fuel in said accelerating reservoir varies, and a starting reservoir from which fuel is drawn to start the engine and to maintain the engine in operation when it is running idle and at slow engine speeds.

3. A carbureter provided with a starting reservoir and an accelerating reservoir arranged in such a manner that the fuel will be drawn from said starting reservoir when the motor is cranked and from said accelerating reservoir when the motor is running at intermediate speeds, said accelerating reservoir communicating with the atmosphere, a nozzle in said accelerating reservoir which supplies liquid fuel to said starting reservoir under certain conditions, said nozzle being arranged so that the fuel will be drawn directly from same by the suction created in the carbureter at intermediate and high speeds of the motor, and being provided with a plurality of ports located at different levels, whereby varying quantities of fuel will enter said nozzle from the accelerating reservoir as the level of the fuel in said reservoir varies.

4. A carbureter provided with a starting reservoir and an accelerating reservoir arranged in such a manner that the fuel will be drawn from said starting reservoir when the motor is cranked and from said accelerating reservoir when the motor is running at intermediate speeds, a nozzle for supplying liquid fuel to both of said reservoirs under certain conditions, said nozzle being arranged so that the fuel will be drawn directly from same into the main air passageway of the carbureter by the suction created at intermediate and high speeds of the motor, and said starting reservoir being so arranged with relation to said nozzle that fuel will flow from said nozzle into said starting reservoir by gravity when the motor ceases to operate, a port for supplying fuel to said nozzle, and means for progressively reducing the suction on said fuel-supply port as the speed of the motor increases.

5. A carbureter provided with a float tank, a starting reservoir and an accelerating reservoir arranged in such a manner that gravity causes liquid fuel to enter both of said reservoirs, means whereby cranking of the motor causes the fuel from said starting reservoir to be introduced into the intake pipe of the motor at a point above

the throttle valve, and a combined fuel-supply inlet and outlet device for the accelerating reservoir, communicating with the float tank and provided with a number of ports located at different levels.

6. A carbureter provided with means for mixing liquid fuel with air and injecting said mixture into the intake pipe of the motor at a point above the throttle valve when the motor is first cranked and when it is running at idle speeds, a vertically-disposed mixing nozzle for supplying a rich mixture of air and liquid fuel to the main suction passageway of the carbureter when the motor is traveling at certain speeds, said nozzle being provided with side ports located at different levels, and means for supplying varying quantities of air and liquid fuel to said nozzle.

7. A carbureter provided with a starting reservoir, an accelerating reservoir, a device for supplying fuel to said accelerating reservoir, the starting reservoir being so arranged that fuel from the accelerating reservoir will flow into same, means terminating inside of the main air passageway of the carbureter for admitting air to said accelerating reservoir so as to vary the suction on said fuel-supplying device as the speed of the motor varies, said reservoirs and fuel-supplying device being arranged below the level of the fuel in the float tank of the carbureter, and a fuel-supply duct leading from said starting reservoir to a point in proximity to the throttle valve.

8. A carbureter provided with a starting reservoir, an accelerating reservoir for supplying fuel to said starting reservoir, a device for supplying fuel to said accelerating reservoir, means for admitting air to said accelerating reservoir so as to vary the suction on said fuel-supplying device as the speed of the motor varies, said reservoirs and fuel-supplying device being arranged below the level of the fuel in the float tank of the carbureter, a mixing chamber provided with a discharge port at a point above the throttle valve, a fuel duct leading from the starting reservoir to said mixing chamber, and means for admitting air to said mixing chamber.

9. A carbureter provided with an accelerating reservoir, a vertically disposed mixing nozzle arranged inside of said reservoir and provided with side ports located at different levels, a fuel-supplying nozzle arranged inside of said mixing nozzle, a starting reservoir arranged to receive fuel from said mixing nozzle, and means for admitting air to said accelerating reservoir.

10. A carbureter provided with a cylindrical-shaped portion, a throttle valve arranged at the upper end of same, a mixing nozzle arranged at the lower end of said cylindrical-shaped portion, means for supplying

liquid fuel and air to said mixing nozzle in varying quantities according to the speed of the motor, and means for causing the heavy particles of fuel that collect in said cylindrical-shaped portion when the motor is throttled down to enter the intake pipe of the motor at a point above the throttle valve, so as to prevent the motor from choking when the throttle valve is opened quickly.

11. A carbureter provided with a cylindrical-shaped portion whose lower end is closed, a throttle valve arranged at the upper end of said cylindrical-shaped portion, a mixing nozzle arranged in such a manner that the fuel is drawn from the same by the suction created in said cylindrical-shaped portion, means for supplying liquid fuel and air to said mixing nozzle in varying quantities according to the speed of the motor, a by-pass leading from the discharge opening in said nozzle to a point above the throttle valve, and means for admitting air to said cylindrical-shaped portion adjacent the upper end of same.

12. A carbureter provided with a cylindrical-shaped portion whose lower end is closed, a partition arranged in said portion so as to form an accelerating reservoir and a starting reservoir, a nozzle for supplying liquid fuel to said accelerating reservoir, a hollow mixing nozzle surrounding said fuel-supplying nozzle and provided at its upper end with a discharge opening which terminates inside of said starting reservoir, said mixing nozzle having side ports located at different levels, means for admitting air to said accelerating reservoir, and a by-pass leading from said starting reservoir to a point above the throttle valve of the carbureter.

13. A carbureter provided with a cylindrical-shaped portion whose upper end flares outwardly and merges into a ring-shaped portion provided with air openings, an open-ended sleeve arranged inside of said ring-shaped portion and provided with a throttle valve, a closure for the open end of said cylindrical-shaped portion, a liquid fuel-supplying nozzle arranged at the lower end of said cylindrical-shaped portion and inside of a vertically disposed mixing nozzle provided with side ports located at different levels, a partition in said cylindrical-shaped portion that divides the interior of same into an accelerating reservoir and a starting reservoir, means for admitting air to said accelerating reservoir above the level of the liquid fuel in same, and a by-pass leading from said starting reservoir to a point above the throttle valve.

14. A carbureter provided with a float tank having a laterally projecting portion, a cylindrical-shaped member combined with said laterally projecting portion and provided at its upper end with a throttle valve,

said cylindrical-shaped portion having a starting reservoir and an accelerating reservoir arranged below the level of the liquid fuel in said float tank, a mixing nozzle in 5 said accelerating reservoir that discharges into said starting reservoir, means for supplying fuel and air to said mixing nozzle in varying quantities according to the speed of the motor, and a by-pass leading from said 10 starting reservoir to a point above the throttle valve.

15. A carbureter provided with a substantially tubular-shaped member whose upper end is enlarged and provided with air openings, an open-ended sleeve arranged inside of the enlarged upper end portion of said member, a throttle valve arranged inside of said sleeve, a partition in said member that divides the interior of the same into an accelerating reservoir and a starting reservoir, 20 a mixing nozzle in said accelerating reservoir

provided at its upper end with a discharge opening from which the fuel flows into the starting reservoir, means for supplying fuel and air to said accelerating reservoir, means for permitting fuel and air to enter said mixing nozzle in varying quantities according to the speed of the motor, a mixing chamber provided with means for admitting air to same, a fuel duct leading from the starting reservoir to said mixing chamber, and means for causing the mixture in said chamber to be injected tangentially into the intake pipe of the motor at a point above the throttle valve when the motor is started. 25 30

In testimony whereof I hereunto affix my signature, in the presence of two witnesses, this fourth day of September, 1913.
